UNITED STATES PATENT OFFICE.

MAURICE L. WILLARD, OF CHICAGO, ILLINOIS, ASSIGNOR TO THE SUPERIOR TYPE COMPANY, OF CHICAGO, ILLINOIS, A CORPORATION OF ILLINOIS.

RUBBER-STAMP BASE.

Application filed November 4, 1925. Serial No. 66,689.

This invention relates to a new and improved rubber stamp cushion construction and more particularly, to such a cushion having retained therein a substantially rigid 5 type holding member.

With certain types of rubber stamps having cushioned bases it is desirable to provide means for holding removable type in association with the remainder of such stamps. 10 This combination is particularly desired in order to print a date which may be varied by means of interchangeable type, in combination with other wording which remains permanently upon the stamp.

15 Attempts have heretofore been made to provide means for retaining type in cushion for forming a cavity in the cushion, the cavity walls being of harder rubber than the remainder of the cushion. This has been 20 difficult because of the inability to secure hard and soft rubbers which vulcanize as a unit at the same heat. Also, such a hard rubber type retaining cavity does not maintain its dimensions in use and this is essential 25 as the removable type must be gripped firmly.

It is an object of the present invention to provide a rubber stamp cushion having a substantially rigid type holding member 30 positively secured thereto.

It is a further object to provide a combination of this character in which the type holding member is removably retained in the cushion.

35 It is also an object to provide such a combination in which the type holding may be formed of metal whereby it will permanently retain its shape and grip upon the type held.

40 It is a still further object to provide a construction in which the substantially rigid type holding member is cushioned upon its lower side by the cushion in which it is carried.

45 Other and further objects will appear as the description proceeds.

I have illustrated certain preferred forms of my invention in the accompanying drawings in which—

50 Figure 1 is a plan view of one form of construction,

Figure 2 is a section taken on line 2—2 of Figure 1,

55 Figure 3 is a section taken on line 3—3 of Figure 2,

Figure 4 is a view similar to Figure 1, but showing a modified form of construction,

Figure 5 is a section taken on line 5—5 of Figure 4,

Figure 6 is a section taken on line 6—6 of Figure 5,

Figure 7 is a view similar to Figure 1, but showing a further modified form,

Figure 8 is a section taken on line 8—8 of Figure 7, and

Figure 9 is a section taken on line 9—9 of Figure 8.

Referring first to the form of construction shown in Figures 1 to 3, the cushion 11 is 70 formed of soft or sponge rubber and has formed therein the cavity 12 which receives the type holding member 13. This member has the ends of its bottom provided with the extensions 14 which underlie the end 75 walls of the cavity 12 and retain the member removably in place in the cushion.

In the form of construction shown in Figures 4 to 6, the cushion 16 has the cavity 17 in which is fitted the type retaining member 18 which has the laterally projecting extensions 19 in the plane of its base. As clearly shown in Figure 6, these extensions 19 underlie part of the side walls of the cavity in the cushion and removably retain 85 the member in place in the cushion.

The form of construction shown in Figures 7 to 9 comprises the cushion 21 having the cavity 22 into which is fitted the type holding member 23. The ends of the member 23 have the extensions 24 which underlie the end walls of the cavity. As a further means of retaining the member 23 in place, the sides of the cavity are provided with lips 25 which overlie the top edges of the member 23 as clearly shown in Figure 9. These lips 25 also cushion the edges of the type holding member when the rubber stamp is in use.

In all of the forms shown the cushion is 100 molded separately from the type holding member and the latter is inserted after the cushion has been vulcanized. The type holding members may be formed of sheet steel and will permanently retain their shape 105 and their ability to securely hold rubber type.

I have shown certain preferred forms of my invention but it is capable of further modification and I contemplate such fur- 110

ther changes and modifications as come within the spirit and scope of the accompanying claims.

I claim:

5. 1. A cushion for rubber stamps, a cavity formed therein, certain of the cavity walls being undercut, and a substantially rigid type-holding member having portions thereof fitting under the undercut cavity walls whereby the type-holding member is removably retained in the cushion cavity.
10. 2. A cushion for rubber stamps, a cavity formed therein, lips overhanging the sides of the cavity, and a substantially rigid type-holding member fitted in said cavity, said member being U-shaped in cross section and the lips on the cavity walls overlying the top edges of the legs of the U.

3. A resilient rubber cushion for rubber stamps, a cavity formed therein, and a sheet metal type-holding member, extensions upon the base of the type-holding member, the member being fitted into the cavity and the extensions removably retaining it in place.

4. A resilient rubber cushion for rubber stamps, a cavity formed therein, and a sheet metal type-holding member, extensions upon the base of the type-holding member, the member being fitted into the cavity and the extensions removably retaining it in place and a portion of the cushion extending below the base of the type-holding member.

Signed at Chicago, Illinois, this 28th day of October, 1925.

M. L. WILLARD.
